CLAIM

The ornamental design for a material spreader, substantially as shown and described.

DESCRIPTION

FIG. 1 is a reduced right side perspective view of a material spreader showing our new design;

FIG. 2 is a front elevational view thereof;

FIG. 3 is a right side elevational view thereof;

FIG. 4 is an enlarged top plan view thereof;

FIG. 5 is an enlarged bottom plan view thereof;

FIG. 6 is a reduced right side perspective view of a second embodiment of FIG. 1.

In FIGS. 3-5, the hitch is shown broken away for ease of illustration.

FIG. 2

FIG. 3

FIG. 4

FIG. 5

FIG. 6
